(57) **CLAIM**

The ornamental design for a toothbrush, as shown and described.

DESCRIPTION

FIG. 1 is a perspective view of a first embodiment of a toothbrush with a removable brush portion in a closed position showing my new design;
FIG. 2 is a first side view thereof;
FIG. 3 is a front side view thereof;
FIG. 4 is a second side view thereof;
FIG. 5 is a rear side view thereof;
FIG. 6 is a top view thereof;
FIG. 7 is a bottom view thereof;
FIG. 8 is a front side view of the removable brush portion thereof, where the removable brush portion is shown separately for clarity of illustration;
FIG. 9 is a front side view of the toothbrush with the removable brush portion removed thereof;
FIG. 10 is a perspective view of a second embodiment of a toothbrush with a removable brush portion in a closed position showing my new design;
FIG. 11 is a first side view thereof;
FIG. 12 is a front side view thereof;
FIG. 13 is a second side view thereof;
FIG. 14 is a rear side view thereof;
FIG. 15 is a top view thereof; and,
FIG. 16 is a bottom view thereof.

1 Claim, 14 Drawing Sheets
